WIRE DRAWING MACHINE

Walther Nacken, Gruna, Germany

Application December 9, 1935, Serial No. 53,646
In Germany February 22, 1935

8 Claims. (Cl. 205—14)

This invention relates to wire drawing machines and more particularly to that type of drawing machines which may be designated as plural wire drawing machines.

5 Wire drawing machines in which the drawing rollers are mounted on horizontal or inclined shafts and the process of wire drawing entirely performed in the drawing solution are at present not being built in any country; this is due to the 10 fact that the places of exit and entrance of the shafts for the drawing rollers from the machine casing into the drawing container cannot be kept perfectly tight, with the result that drawing liquid will be liable to enter the adjacent casing 15 which contains the gear-mechanism of the machine.

According to my invention this drawback is obviated by the provision of one or more intermediary chambers between the place of passage 20 of the drawing roller shaft through the wall of the gear-casing and the place of entrance of said shaft into the liquid container, so that all drawing liquid entering said intermediary chamber from said drawing container will be carried away 25 into the supply-container. According to my invention furthermore, there is eventually provided a baffle-plate or the like on the drawing roller shaft in the intermediary chamber, said plate enclosing said shaft sufficiently tight to prevent 30 particles of the drawing liquid passing along said shaft and entering the gear-casing.

In the accompanying drawings I have represented some examples of construction of my present wire drawing machine. Fig. 1 shows one 35 construction partly in a side-view and partly in section, Fig. 2 is a plan-view taken on Fig. 1, and Figs. 3 and 4 illustrate arrangements and constructions of the aforesaid intermediary chambers different from those shown in Figs. 1 and 2. Fig. 5 is a diagrammatic view of a system illustrating a number of wire drawing machines and a collecting container, and Fig. 6 is a side view 40 partly in section showing a modified construction.

Referring now more particularly to the drawings, the gear-casing 1 and the drawing container 3 are arranged above the supply-container 2. The drawing solution is conveyed from said supply-container 2 into said drawing container 3 by means of a pump, whenever said latter container is to be filled. The drawing container 3 45 may easily be emptied by opening a valve placed in a discharge-conduit that connects said two containers with each other.

On the shafts 4 and 5 at their ends positioned 50 within the drawing container 3 are mounted the

drawing rollers 6 and 7, respectively. Said shafts 4 and 5 are mounted in bearings 8, 9 and 10, 11 provided in the walls of the gear-casing 1. Driving power is supplied to said shaft 4 by means of the pulley 12 and transmitted from said shaft 5 5 to the shaft 5 by way of the gear-wheels 13, 14 and 15.

The shafts 4 and 5 now, according to my invention, extend from the gear-casing 1 into the drawing container 3 not immediately but through 10 the intermediary chambers 16 and 17, respectively, said chambers being formed by properly shaping at proper places the wall 30 of the drawing container.

At the place of entrance of the shafts 4 and 5 15 into the drawing container 3 there are provided stuffing boxes or tightening devices 18 and 19, respectively.

In order to safely prevent particles of liquid from flowing alongside the shafts 4 and 5 through 20 the stuffing boxes 18 and 19 as far as into the gear-casing 1, a baffle-disk 21 is mounted on either shaft 4 and 5 in such a manner that said baffle-disks will surround said shafts perfectly 25 closely. The particles of drawing liquid which may eventually pass through the stuffing-boxes 18 and 19 will now be thrown-off by said baffle-disks and fall into the supply-container 2 and then back into the container 3 by means of a 30 pump, not shown.

The construction so far described may of course be modified in a great variety of ways. In particular, there is no absolute necessity of tightening the drawing shafts 4 and 5 by means of stuffing boxes or packings 18 and 19 at the places of 35 entrance into the drawing container.

Instead of the stuffing boxes or packings 18 and 19 there may also be provided acid-proof bearings 55 (Fig. 6) at the above indicated places. Such bearings 55, moreover, need not surround 40 the respective drawing shafts liquid-tight and a small interstice 56 may also be provided between said shafts and the bearing-shells to permit a permanent and uniform flow of the drawing liquid through said interstice and subsequent deflection of said flow by the baffle-disk 21 to cause 45 said liquid to be returned to the supply-container 2. A construction of this kind would result in the considerable advantage that the drawing 50 roller shaft is given an additional support immediately in front of the drawing cone.

In case a bearing is provided at the place of entrance of the drawing roller-shaft into the drawing container, the bearings 9 and 11 may be 55

dispensed with or replaced by packings or stuffing boxes.

It is furthermore by no means necessary to give to the wall 30 adjacent the gear-casing 1 a proper conformation for enclosing the intermediary chambers 16 and 17, as said wall 30 may also be constructed in the manner shown in Fig. 3. In this case an interstice 23 is provided between said wall 30 and the adjacent wall 1' of the gear-casing 1, with the intermediary chambers 31 and 32 are fastened to said wall 30.

With machines operating at small speed in which a spraying-about of the drawing liquid is not to be feared, there is no necessity of providing a special chamber for each drawing shaft 1; in this case it is possible to use a single intermediary chamber common to all drawing shafts by omitting the intermediary chambers 31 and 32 shown in Fig. 3 and substituting therefor the supporting walls 41 by means of which the intermediary container is fastened to the gear-casing, said walls serving as lateral walls of the common intermediary chamber. In this case it will be necessary to shield the two bearings 9 and 10 shown in Fig. 1 by protective covers 22 against the sprayed-off particles of the drawing liquid.

Although it may be of advantage to arrange the supply-container for the drawing liquid immediately underneath the drawing container, it will be possible to arrange the supply-container separate from the drawing container. In such case a common supply-container or collecting container 53 (Fig. 5) may be provided for a plurality of wire drawing machines and installed at a proper place of the plant. The supply container 50 for each machine will thus solely serve as a collecting container from which the drawing liquid is conveyed to the main container. Each container 50 has an outlet 51 and a main conduit 52 to the container 53. A pump 54 forces the liquid back to the drawing containers 3.

In the examples of construction described hereinabove it is furthermore not necessary to mount the drawing shafts in exactly horizontal position, it being also possible to have these shafts positioned in more or less inclined direction with respect to the horizontal plane.

In order to have the front bearing for the drawing shaft positioned in close proximity to the drawing rollers 6 and 7 I propose to make use of the construction shown in Fig. 4. In this construction the walls of the intermediary chambers are made in the shape of a bell and fastened to the wall 30 of the drawing container 3 by means of a flange as shown in Fig. 4. Within the bell-shaped wall 33 and 34 of the intermediary chamber there are provided baffle-plates 35 of likewise bell-shaped conformation, said plates surrounding the drawing shafts by means of an oblong hub, the baffle-plates 35 and 36, however, being also equipped with a front ball-bearing 28 and 29. The outer ring of these ball-bearings is supported by means of a sleeve or bushing 37 and 38 fast on the gear-casing; grooves 39 and 40 are provided at the outer side of said sleeves 37 and 38 to prevent access of drawing liquid from the intermediary chamber to the ball-bearings 28 and 29.

Above the drawing disks there may be provided protective plates 43, swingable in upward direction, in order to prevent a spraying-about of the drawing liquid at higher speeds. Since the drawing rollers as a rule are used in pairs and the drawing container is divided into several compartments in case of larger machines, while

each of said compartments contains a pair of drawing rollers, it is advisable to construct said protective plates 43 in the manner shown in Fig. 2 to always cover one pair of drawing rollers. Each protective plate 43 is journaled by means of several hinges 44 to the rear wall of the container 3 or to some auxiliary member 45 permitting upward swinging motion of said plates in order to permit the wire to be drawn into the machine.

The lateral rims 46 of the protective plate are bent downward as shown in the drawing in order to prevent motion of the liquid due to rotation of the drawing rollers against coming into action at the surface of the liquid. In other respects the protective plates, as to form and arrangement, should be constructed to meet special conditions.

I claim:

1. A wire drawing machine comprising horizontal drawing shafts, a container for a drawing liquid, a gear casing, a gear mechanism for said drawing-shafts mounted in said casing, said casing and said container having an interstice between them and separated from them by walls, bearings for said drawing-shafts traversing a lateral wall of said container beneath the plane of the surface of the drawing liquid, and a supply container to receive any drawing liquid which may leak through the bearings of the drawing shafts, the traversing place of each drawing-shaft through said wall being separated from said casing by said interstice connected with the supply container arranged lower than said first-mentioned container.

2. A wire drawing machine, as specified by claim 1, in which the container for the drawing liquid is supported separate from the gear-casing, said machine including intermediary chambers provided in the interstice within the range of the places of passage of said drawing-shafts through said container for drawing liquid, said intermediary chambers being positioned at the rear of said latter container, the rear-wall of said chambers adapted to prevent access of drawing liquid to said bearings.

3. A wire drawing machine according to claim 1, in which the container for the drawing liquid and the gear casing are mounted above the supply container, and in which chambers are provided intermediate said container for the drawing liquid and the casing and opening toward said casing.

4. A wire drawing machine according to claim 1, in which a baffle disk is mounted on each shaft within the interstice and in which a special protective cover is provided for each shaft within range of each bearing to prevent the liquid thrown off of the baffle disk from reaching the bearing.

5. A wire drawing machine according to claim 1, in which an intermediary chamber is provided positioned between the container for the drawing liquid and the casing and is common to all of the drawing shafts.

6. A wire drawing machine according to claim 1, in which a collecting-container is provided for said liquid when discharged from said machine, said collecting-container being positioned underneath said container for the drawing liquid and said gear-casing, and in which a connecting conduit is provided between said collecting-container and said supply-container.

7. A wire drawing machine according to claim 1 in which an intermediary chamber and a baffle are provided, the wall of said intermediary chamber as well as said baffle being of bell-shaped con-

struction to enclose the bearing of the respective drawing-shaft, and in which a bushing is provided fast on said casing and adapted to support said bearing.

5 8. A wire drawing machine according to claim 1, in which drawing-rollers are provided mounted on said drawing-shafts, said rollers and said

shafts being positioned approximately horizontal, and in which protective plates are provided covering up a pair of said rollers, the under edge of said protective plates being positioned underneath the level of the drawing liquid in its container. 5

WALTHER NACKEN.
